CLAIM

The ornamental design for a brake actuator housing, as shown and described.

DESCRIPTION

FIG. 1 is a top plan view of the brake actuator housing.

FIG. 2 is a bottom plan view of the brake actuator housing.

FIG. 3 is a side elevation view of the brake actuator housing.

FIG. 4 is a side elevation view of the brake actuator housing.

FIG. 5 is an end elevation view of the brake actuator housing.

FIG. 6 is an end elevation view of the brake actuator housing; and,

FIG. 7 is a top perspective view of the brake actuator housing.

The broken line showing of environment is for illustrative purposes only and forms no part of the claimed design.
